Inventor

Frederick M. Goddard,
By his Attorney

James F. Duhamel,

UNITED STATES PATENT OFFICE.

FREDERICK M. GODDARD, OF BROOKLYN, NEW YORK.

HEDGE-TRIMMER.

1,272,795.

Specification of Letters Patent. Patented July 16, 1918.

Application filed December 5, 1916. Serial No. 135,103.

To all whom it may concern:

Be it known that I, FREDERICK M. GODDARD, citizen of the United States, and resident of Brooklyn, in the county of Kings 5 and State of New York, have invented certain new and useful Improvements in Hedge-Trimmers, of which the following is a specification.

This invention relates to hedge trimmers 10 and its object is to provide a circular base plate with a cutting edge and to mount in a frame on the base a motor adapted to rotate a cutting blade, the frame acting as a handle and having controlling means for 15 the motor which may be operated while the trimmer is held in position for work, as will be more fully described in the following specification, set forth in the appended claims and illustrated in the accompanying 20 drawings which form a part of this application and wherein:

Figure 1 is a plan view of the improved trimmer.

Fig. 2 is a side view of the same.

Fig. 3 is a sectional view through the base and rotating blade.

Fig. 4 is an enlarged detail view of the switch.

Fig. 5 is a longitudinal sectional view 30 through the same.

The improved hedge trimmer consists of a circular base plate 10 with suitable openings 11 to lighten its construction and around the edge of its under side is secured 35 a fingered ring 12 constituting an annular blade. Adapted to rotate in close proximity to this ring is a disk 13 with cutting teeth and coöperating with the ring 12 to constitute the cutting blade of the trimmer and is 40 mounted at the end of the shaft 14 of a motor 15, the shaft being journaled in ball bearings 16 in a perforation at the center of the base plate.

The motor 15 is mounted by means of 45 bolts 17 in a frame comprising arms 18 and a ring 19, the motor being held above the surface of the base by this ring, and abundant space is left about the arms 18 so they may be grasped by the operator and the 50 work of the trimmer directed.

At one side of the base plate 10 is a hollow arm 20 adapted to be used as handle and having a switch at its outer end by which the electric current for operating the motor 55 may be controlled, and this switch consists of a disk 21 with a slot 22 and contact point

23 and mounted on the arm between the insulating hubs 24 and 25. In the slot is a spring 26 under compression and bearing against the stud 27 so that normally the contact points 23 and 28, the latter being in the hub 24, are disconnected; but when it is desired to supply the motor with the electric current to rotate the blade 13 the disk is thrown around by one of the fingers of the 60 hand holding the handle 20. The points 23 and 28, as shown in Fig. 5, are part of an electric circuit whose wires 30 pass through the handle to the motor and may be connected to any desired source of electrical 65 energy.

As will be seen in Fig. 3 the lower end of the armature shaft 14 is supported in the plate 10 by ordinary anti-friction cones and ball bearings and the upper cone may be adjustable so that the proximity of the blades 70 12 and 13 can be regulated to afford proper adjustment for efficient work.

In operating the trimmer one of the hands grasps the handle 20 with the thumb so located that it may shift the disk 21 by means of its extension and the other hand catches one of the arms 18. The trimmer may then be held against the hedge and moved in the direction the trimming is to be done, operating 85 on a vertical or a horizontal face.

By the arrangement of the switch at the end of the handle the blade stops the instant of release by the operator and serious damage may be thus obviated were the cutter 90 permitted to rotate.

It is obvious that any type of motor may be used and that the device may be otherwise arranged and modified without departing from the essential features above described, or from the scope of the appended 95 claims.

What I claim as new is:

1. In a hedge trimmer, the combination with a circular base having a cutting edge, 100 of a circular blade coöperating with the cutting edge, a motor carried by the base and rotating the circular blade, radial handles on the base and arranged about the center of the edge and blade and supporting the 105 motor, and a controller for the motor on a handle and adapted to be operated as the trimmer is held in its working position.

2. In a hedge trimmer, the combination with a base plate having a cutting edge, of 110 a coöperating rotating blade, a spider radiating from a center common to that of the

blades, a motor carried by the spider, a shaft for the motor and carrying the rotating blade, anti-friction cones supporting the shaft, and adapted to regulate the proximity of the blade and the cutting edge, and a controller for the motor carried by a handle.

3. In a hedge trimmer, the combination with a circular base plate having an opening 5 at its center, of a cutting edge on the plate, 10 handles on the upper side of the plate, a

motor above the opening in the base plate and supported by the handles, a switch for the motor in a circuit therefor and on one of the handles, a shaft for the motor and passing through the opening, and a circular blade at the end of the shaft and coöperating with the cutting edge. 15

Signed at New York city in the county of New York and State of New York this 24th 20 day of November A. D. 1916.

FREDERICK M. GODDARD.
